UNITED STATES PATENT OFFICE.

JACOB G. SCHIUMM, OF LA PORTE, INDIANA.

DESIGN FOR A CABINET.

SPECIFICATION forming part of Design No. 23,907, dated December 25, 1894.

Application filed November 2, 1894. Serial No. 527,767. Term of patent 7 years.

To all whom it may concern:

Be it known that I, JACOB G. SCHIUMM, a citizen of the United States of America, residing at La Porte, in the county of La Porte and State of Indiana, have invented and produced a new and original Design for Cabinets, of which the following is a specification, reference being had to the accompanying drawing, and to letters of reference marked thereon, 10 which forms a part thereof.

This design relates to cabinets for the display of merchandise, especially confectionery and like goods, and consists of an octagonal inclosing case A which is mounted on an octagonal base from which extend vertical columns C with support at top having a molding D and pillars or short columns E which terminate in spheres e, the columns E being connected by a suitable molding F.

15 20 Between each of the columns or posts C are panels, one of the panels being mounted in a frame which is carried by one of the posts C.

Within the vertical case so as to be visible through the panels is a frame supported by a vertical post G with longitudinal corrugations, horizontal shelves being supported by the post and by vertical columns which extend from the outer edge of the base upwardly. 25

Between the vertical columns are cross-bars II and inclined bars I, the panels formed by 30 the vertical columns of the cross-bars II carrying plates, and shelves, the shelves being divided by the division plates into eight triangular compartments.

I claim as my invention— 35

The design for a cabinet herein shown and described.

In testimony whereof I affix my signature in presence of two witnesses.

JACOB G. SCHIUMM.
